UNITED STATES PATENT OFFICE.

FREDERICK W. JOHNSON, OF WALTHAM, MASSACHUSETTS.

NON-REFILLABLE BOTTLE.

1,186,581.

Specification of Letters Patent. Patented June 13, 1916.

Application filed June 5, 1914. Serial No. 843,132.

To all whom it may concern:

Be it known that I, FREDERICK W. JOHNSON, a citizen of the United States, residing at Waltham, in the county of Middlesex and State of Massachusetts, have invented new and useful Improvements in Non-Refillable Bottles, of which the following is a specification.

This invention relates to a non-refillable bottle, the object of the invention being to provide greater freedom in the outpour from the bottle and to more effectually prevent the possibility of refilling the bottle after the same has been emptied and also to provide a bottle which will pour equally well in a variety of positions.

The invention consists in certain novel features and details of construction hereinafter fully described in the specification and pointed out in the claim.

Referring to the drawings: Figure 1 is a section, partly in elevation, through the neck of a bottle having my improved device applied thereto, the bottle being broken away to save space. Fig. 2 is a section similar to Fig. 1 showing the position of the parts when the bottle is adapted to pour out the liquid which it contains. Fig. 3 is a section, partly in plan, taken on line 3—3 of Fig. 1. Fig. 4 is a section taken on line 4—4 of Fig. 1. Fig. 5 is a side elevation of the cylindrical sleeve which renders the bottle non-refillable. Fig. 6 is another side elevation of the sleeve as viewed from the opposite side of that illustrated in Fig. 5. Fig. 7 is a diagram view illustrating a development of the periphery of the cylindrical casing or sleeve.

Like numerals refer to like parts throughout the several views of the drawings.

In the drawings, 10 is the bottle, 11 the bottle neck and 12 is a cylindrical sleeve which is inserted in the neck of the bottle and securely fastened thereto either by cement or otherwise as may be desired. The sleeve 12 has an interior chamber 13, the upper end of which is closed by a plug 14 fastened to said sleeve by a cross-pin 15. The chamber 13 is open at the lower end thereof and opens into the interior of the bottle neck 11. A cylindrical valve 16 is slidable longitudinally within the sleeve 12 and is adapted to rest normally upon an annular flange 17, constituting a seat, formed adjacent to the lower end of said sleeve. The sleeve 12 is provided with two exterior recesses which, with the bottle neck, form

chambers 18 and 19. These chambers are oppositely disposed and are substantially duplicates of each other.

A port 20 leads from the interior chamber 13 into the exterior chamber 18 and another port 21 leads from the interior chamber 13 into the exterior chamber 19. The chamber 18 has a passage 22 leading from the lower end thereof to the upper end of the sleeve 12 and has also a passage 23 leading from the upper end of said chamber to the upper end of said sleeve. The chamber 19 has a passage 24 similar to the passage 22 leading from the lower end of the chamber 19 to the upper end of the sleeve 12 and another passage 25 leading from the upper end of said chamber 19 to the upper end of said sleeve 12. The chambers 18 and 19, the ports 20 and 21, the passages 22 and 24 and the passages 23 and 25 are substantially duplicates and are oppositely disposed to each other, respectively. The sleeve 12 has another port 26 leading from the interior chamber 13 to the exterior of said sleeve adjacent to the upper end thereof and into a passage 27 leading from the port 26 to the upper end of said sleeve 12. The port 26 and passage 27 constitute an air outlet independent of said chambers 18 and 19 to allow the air to pass out from the interior of the sleeve 12 when the bottle is inverted and the valve 16 slides toward the outlet end thereof. Said port 26 and passage 27 allow the air to enter when the bottle is stood upright and the valve returns to its seat. As before described when the bottle is inverted and the valve 16 slides from the position illustrated in Fig. 1 to that shown in Fig. 2, the air will pass out of the port 26 and passage 27, thus allowing said valve to slide freely.

Under normal conditions when the bottle is in the position illustrated in Fig. 1 the valve rests upon the annular valve seat 17 and when in this position it will be seen that it will be impossible to introduce a wire into the interior of the sleeve for the purpose of lifting the valve from its seat and introducing liquid into the interior of the bottle.

Assuming the bottle to be filled with liquid and it is desired to pour some of said liquid out of said bottle, said bottle is inclined to the position illustrated in Fig. 2. The valve 16 will slide down the interior of the sleeve in the chamber 13 until it rests against the plug 14 as shown in Fig. 2. The

bottle is held, in order to secure the best results, with one of the passages 22 uppermost. When in this position the port 20 will be above the port 21, the liquor will 5 then flow out of the port 21 into chamber 19 and out of the passages 24 and 25 while the air will pass through the passage 22 and the port 20 into the interior chamber 13 and into the interior of the bottle. At the 10 same time that the air enters the passage 22 and port 20, as described, any liquid which may be in the chamber 18, due to previous use of the bottle, will pass out through the passage 23. Upon returning the bottle 15 to an upright position the valve 16 will return to the position illustrated in Fig. 1 resting upon the seat 17.

The liquor will pour equally well from the bottle if, instead of holding the bottle 20 as hereinbefore described, the passage 24 is held uppermost when the bottle is inclined at an angle, as in Fig. 2, and under these 25 conditions the liquor will pass out through the port 20 into the exterior chamber 18 and out through the passages 22 and 23 while air will enter the bottle through the passage 24 and port 21 and any liquor remaining in the chamber 19 will pass out through the 30 passage 25. It will thus be seen that all liquor will pour freely because there are two 35 passages in each case, namely, 24 and 25 or 22 and 23 according to the position in which the bottle is held through which it may pass to the exterior of the bottle, it being immaterial to the practical working of the 40 device whether the bottle is held in its decanted position with the passage 22 uppermost or with the passage 24 uppermost, said 45 chambers 18 and 19, ports 20 and 21, passages 22 and 24 and passages 23 and 25 being duplicates of each other and oppositely disposed to each other, respectively.

It will be noted that the chamber 13 is slightly tapered outwardly from the lower 45 to the upper end thereof, so that as the valve slides away from the seat it will slide freely

and as it slides onto the seat it will finally come to a bearing not only on said seat but all around its periphery on the inner tapered wall of said sleeve, thus firmly fitting in 50 position when on the seat and moving comparatively loosely within said chamber 13 when it is off of its seat.

Having thus described my invention, what I claim and desire by Letters Patent 55 to secure is:

A bottle having, in combination, a cylindrical sleeve located in the neck of said bottle, said sleeve having an interior chamber closed at the upper end and open at the 60 lower end thereof, said sleeve having two independent oppositely disposed exterior recesses forming with said neck, two independent exterior chambers diametrically opposed ports connecting each of said exterior chambers with said interior chamber, a passage leading from the lower end of each exterior chamber to and out of the upper end of said sleeve, a passage leading from the upper end of each exterior chamber to and out of the upper end of said sleeve, another port leading from said interior chamber to the exterior of said sleeve adjacent to the upper end of said sleeve, a passage leading from said last named port to and out of the 65 upper end of said sleeve and constituting an air outlet independent of said exterior chambers each of said passages before mentioned being formed in the periphery of said sleeve, and a valve slideable longitudinally within said interior chamber alternately out of and into alignment with said diametrically opposed ports and arranged to rest normally upon a seat provided therein adjacent to the lower end of said sleeve, 70 75 80 85

In testimony whereof I have hereunto set my hand in presence of two subscribing witnesses.

FREDERICK W. JOHNSON.
